FOUR-PART CORSET

Vera Giegerich, Los Angeles, Calif., assignor to
Alax Tillo, Beverly Hills, Calif.

Application January 29, 1946, Serial No. 644,041

2 Claims. (Cl. 2-43)

1

My present invention, in its broad aspect, has to do with improvements in corsets wherein each half of the corset is formed of four parts, and wherein the lower part of the corset covers the lower part of the body, including the seat, and the wearer is compelled to sit on the corset, thereby preventing the corset from riding up. My corset is designed for women who have normal abdomens and waist measures, and is so constructed and fitted as to give the wearer greater freedom of movement, and give the figure a slenderized and more natural and elegant appearance while properly and comfortably supporting the abdominal muscles in their normal position. My corset has elastic panels at the sides and a triangular front elastic gore at the lower edge of the front panel, and has a seam controlling the abdominal fitting, and another seam controlling the fitting of the curves of the lower part of the back panel of the corset to force the wearer to sit on the corset. Each elastic side panel is connected at its front edge with a narrow fabric panel which in turn is connected with the front panel, while the rear edges of the elastic panels are connected with the side edges of the back panels. My corset is relatively simple in construction and is easily fitted to individual figures, and affords greater comfort, and increases the attractiveness of the figure to which it is applied while properly and comfortably supporting the organs of the body, and allowing greater freedom of movement.

Other and equally important objects and advantages of my invention will be apparent from the following description and drawings, and it is pointed out that changes in form, size, shape, materials, and construction and arrangement of parts is permissible and within the purview of my broad inventive concept, and the scope of the appended claims.

Figure 1 is a perspective view of a corset constructed in accordance with the present invention;

Figure 2 is a side elevation;

Figure 3 is a section on the line 3-3 of Fig-

ure 2;

Figure 4 is a back view;

Figure 5 is a view showing one-half of a front panel and of one of the side panels;

Figure 6 is a view of an elastic panel and of one-half of a back panel.

In the drawings, wherein like characters of reference are used to designate like or similar parts:

The numeral 1 designates the front panel which

has a triangular elastic gore 2 at its bottom edges, with the sections of the bottom edge to either side of the gore angled upwardly, as at 3, to the gores. The garters 4 are attached to the front panel at either side of the gore. I provide at each side an elastic panel 5 the front edge of each of which is attached to a narrow fabric panel 6 each of which is attached in turn to the side edges of the front panel. The upper part of the seam at one side between the front panel and narrow side fabric panel is open and provided with a zipper or hook fastener 7. Attached to the back edges of the elastic panels are the side edges of a back panel 8. All of the panels are hemmed at top and bottom as at 9.

Referring to Figures 5 and 6, the panels are divided and formed into areas associated with various parts of the figure; the top area 10 extends down to waist line 11. Area 12 extends from the waist line 11 to the line 13 and covers the upper hips, and the area 15 extends from upper hip line 13 to the lower hip line 14. The hollow area 16 of the corset extends from the lower hip line 14 to the bottom edge. In assembling the panels the angled waist lines 17 and 18 of the front panel 1 and narrow side panel 6 are taken with the waist line of the elastic and back panels, and this applies also to the lines of the upper and lower hips.

In fitting the corset for the abdomen, line 19 is used and for the curve of the bottom to compel a person to sit on the corset, the line 20 is used. From the lines 21, 22, 23 and 24 the general outline of the panels is formed as shown in the heavy full lines of the panels. In Figure 6 the area between lines 24-25 serves for lacer space when desired. In line 26 when lacer space is not required the lacing area between 24-25 may be reduced in accordance with the desire of the manufacturer and requirements as developed by the elastic used.

It will be apparent that the various respective areas as, for example, the four areas designated 10 in Figures 5 and 6 will be considered together as to the requirement of their total size and that the side lines of the panels will be formed accordingly. This is true for all the respective areas and makes for an extremely accurate fitting while at the same time providing a corset having a maximum of smooth uninterrupted surface.

The present application is to be distinguished from my co-pending application, Serial No. 644,040, filed on January 29, 1946, wherein I have provided a corset having four parts in each side and which corset is designed for women

whose lower hips measure more than forty inches, whereas in the present application I have provided a corset particularly designed for women whose similar measurement is less than forty inches.

From the foregoing it is believed that the construction, operation and advantages of my invention will be apparent, but it is again emphasized that interpretation of its scope should only be conclusive when made in the light of the subjoined claims.

I claim:

1. A corset comprising a plurality of vertically disposed panels including a front panel at the center of the front, complementary side panels adjoining the front panel, a back panel at the center of the back, and complementary elastic panels joining the edges of the back panel to the side panels, said panels having top areas above the waist line, waist line areas, upper hip areas, lower hip areas, and bottom areas, the adjoining side edges of the front and side panels, side and elastic panels, and elastic and back panels forming a straight line between panels, triangles with the vertexes on the waist line and with the sides meeting the bases with acute angles and the

5 adjoining sides of the bottom areas of the front and side panels and elastic and back panels forming acute triangles between the lower hip areas and lower ends of the panels with the vertexes on the lower hip areas, whereby the lower ends of the panels are drawn together reducing the area of the lower end of the corset.

10 2. The method of constructing a corset having each side formed of four vertically extending panels including a panel of elastic material, of first dividing each panel into a top area, a waist line area, an upper hips area, a lower hips area and a bottom area and then shaping the sides of the panels with respect to the desired combined size of the respective areas.

VERA GIEGERICH.
